UNITED STATES PATENT OFFICE.

BIAGIO INTINGARO, OF NEW ROCHELLE, NEW YORK.

DESIGN FOR A RADIATOR-CAP ORNAMENT.

Application filed April 23, 1929. Serial No. 30,989. Term of patent 14 years.

To all whom it may concern:

Be it known that I, BIAGIO INTINGARO, a citizen of the United States, and a resident of New Rochelle, in the county of Westchester and State of New York, have invented a new, original and ornamental Design for a Radiator-Cap Ornament, of which the following is a specification.

Reference is to be had to the accompanying drawing forming a part hereof in which the figure is a perspective view of a radiator cap ornament embodying my new design.

I claim—

The ornamental design for a radiator cap ornament as shown.

Signed at New York in the county of New York and State of New York this 22nd day of April 1929.

BIAGIO INTINGARO.
